UNITED STATES PATENT OFFICE.

FRANK M. FRIESELL, OF SAN FRANCISCO, CALIFORNIA.

BOX-CAR-DOOR HANGER.

Application filed July 25, 1922. Serial No. 577,327.

To all whom it may concern:

Be it known that I, FRANK M. FRIESELL, a citizen of the United States, residing at the city and county of San Francisco and 5 State of California, have invented new and useful Improvements in Box-Car-Door Hangers, of which the following is a specification.

This invention relates to doors and especially to a box car door and a hanger therefor.

The object of the present invention is to generally improve and simplify structures of the character described; to provide a door 15 which is laterally and longitudinally movable with relation to the opening to be closed; to provide a novel hanger or mounting which cooperates with said movement; to provide a door which may be readily and 20 efficiently sealed in closed position, and which presents a flush surface with relation to the side of the car when closed to reduce wind loads to a minimum. Further objects will hereinafter appear.

25 One form which my invention may assume is exemplified in the following description and illustrated in the accompanying drawings, in which—

Fig. 1 is a partial side elevation of a rail-way box car showing the application of the invention.

Fig. 2 is a partial plan view thereof the car wall being shown in section.

Fig. 3 is a vertical cross section.

35 Figs. 4 and 5 are front and side views respectively of a door hanging plate.

Fig. 6 is a perspective view of one of the bracket arms.

Fig. 7 is a front view of one of the bracket 40 arm supporting brackets.

Fig. 8 is a longitudinal central section showing the arrangement of the sealing medium.

Referring to the drawings in detail, and 45 particularly to Figs. 1, 2 and 3, A indicates the roof of a box car, 2 the side thereof, 3 the opening through which the freight is entered and removed, 4 the door by which said opening is closed, and 5 a track upon 50 which the door is longitudinally movable. The track as illustrated is substantially channel shaped in cross section and the lower flange portion thereof forms the rail upon which the door is longitudinally movable, 55 said movement being obtained by supporting the door with relation to the track by

means of hanger plates 6 and rollers 7 journaled thereon. The rollers are flanged in the usual manner and are turnable about pins 8, which in this instance are formed 60 as an integral part of the plates 6. These plates are bolted to the door as shown and two or more may be employed as desired. Each plate is also provided with an outwardly projecting lug 9 which extends in 65 under the track 5 and as such serves as a guard to prevent jumping of the rollers with relation to the track or disengagement from the same. Stops are provided at each end of the track to limit the longitudinal 70 movement of the door and the method of positioning one of said stops will hereinafter be described.

The door has a lateral and longitudinal movement with relation to the opening to be 75 closed and this is also true of the track 5, the only difference being that the longitudinal movement of the track is exceedingly limited when compared with the movement of the door. To permit lateral and longitudinal movement of the track 5, pivotally supported bracket arms 10 are employed. These arms are pivotally secured on their inner ends on pins 11, which are formed as 80 integral parts of plates 12 and the opposite ends are pivotally connected to the track 5, as at 13, by pins 14 formed as integral parts of plates 15. The plates 12 and 15 and the pins 11 and 14 are identical in construction, the plates 12 being secured to the side of 85 the car by means of bolts or the like as shown at 16 and the plates 15 are similarly secured to the track 5 by means of bolts or the like, a detail view of the plates 12 and 15 and the pins carried thereby being shown 90 in Fig. 7. The pins are slightly tapered as shown to take up any wear which may take place and the holes in the arms 10 are similarly tapered and the tapers are reversed at the opposite ends of the arms to render the 95 arms reversible.

By mounting the track in the manner disclosed, it can be seen that when the track is 100 swung in a forward direction it will lie flush with the side of the car and that when moved in the opposite direction an outward or lateral movement will first take place and as the end of the movement is reached, a substantially parallel position of the track will 105 be assumed with relation to the side of the car, further movement will, however, not take place as means for preventing such 110

movement is provided as will hereinafter be described.

The door proper may be constructed in any suitable manner, but is in most instances 5 encased or surrounded by strap iron as indicated at 18. The sides and top of the door opening are similarly lined with strap iron as indicated at 19. The opening presented by the straps 19 is slightly less than 10 that presented by the straps 18 and as both straps are slightly extended beyond the surfaces lined, as shown in Fig. 8, overlapping of the straps will take place and a sealed joint between the door and the car 15 may be readily formed by the insertion of a piece of burlap, tar paper or the like indicated at 31. The door may be provided with any form of lock desired, but a three-bolt lock is in this instance illustrated, the three 20 bolts being indicated at 20, 21 and 22, and all bolts being extended and retracted in unison by means of a centrally disposed operating arm 23, to which they are pivotally attached. The bolts are guided by keepers 25 secured on the door and when projected enter keepers secured on the side of the car and above the door opening, these keepers being indicated at 24. The lower edge of the door is in most instances guided by means of a 30 channel iron, but is in this instance guided by a series of malleable or steel brackets such as indicated at 25. These brackets serve the same function as a continuous piece of channel iron, but they are more practical as 35 the channel iron is more readily bent or damaged by trucks backing into the car, etc. Such bending of the channel arm often jams the doors and renders the operation of opening and closing the door exceedingly difficult. If one of the brackets here illustrated 40 should be bent, it is obvious that it would be a simple matter to straighten the same to prevent interference with the door.

In actual practice, assuming that the door 45 is closed as shown in Fig. 1, and that it is desired to open the same, it will only be necessary to partially rotate the lever 23. Such turning movement releases the bolts 20, 21 and 22 with relation to the keepers 24, 50 and the door thus unlocked is free to be opened. This is accomplished by first pulling outwardly on the door, such outward movement causing the bracket arms 10 to swing outwardly about their pivotal supports and the door is in this manner swung laterally or outwardly from the opening 55 which it closes. When completely extended, longitudinal movement is imparted to the door and it will then slide along the track until the door has been completely 60 opened, being here prevented from further movement by stationary door stops as indicated at 28. As previously stated the track 5 swings outwardly until the arms 10 are 65 extended when the door is moved outwardly

from the opening which it closes. Further movement of the arms is prevented when longitudinal movement is imparted to the door as a strap 29 secured on the inner side of the door will then engage the keeper indicated at 24^a and slide along the surface of the same, thus preventing inward movement of the track and the door when it is being opened. A forward stop is formed on the track as indicated at 30. This stop is riveted 75 welded or otherwise secured to the track after the door is hung as its position can then be readily determined, that is after the tracks, hangers and door have been placed in position, the door is slid along the track so until it substantially registers with the door opening. The stop member 30 is then secured and as the door engage the stop, the track will swing inwardly and thus impart an inward movement to the door. 85

The present invention embodies many important advantages: First, a large reduction in the cost of hanging a door is obtained by the ease with which the brackets, hangers, arms, etc., can be attached. Second, a door is provided which when closed is flush with the side of the car and as such reduces wind load resistance to a minimum. Third, a perfect assurance of weather-proofing, cinder-proofing, etc., is obtained, thus permitting the carrying of grain and other materials in bulk and eliminating the necessity of employing lumber or other source of sealing as required by the Interstate Commerce Commission, this being particularly 95 true when shipping explosives. Fourth, the door structure here shown does away with undue loss of time, labor and breakage of the cars and doors, due to the fact that any internal pressure exerted against the door 105 will aid in opening the same. That is the door in this instance swings out a distance to approximately four inches from closed position and then slides along the side of the car where considerable clearance is 110 maintained. For this reason internal pressure is released the moment the door is opened and the difficulties usually encountered in ordinary doors are eliminated. Breakage of the door, etc., is also avoided as 115 the use of pinch bars and the like will be unnecessary. Fifth, large bearing pins may be employed for the rollers from which the door is hung and longitudinal movement is 120 therefore readily imparted and danger of the rollers jumping the track is also avoided due to the use of the lugs 9. Sixth, practically any form of locking device may be employed and particularly a three-bolt lock 125 as here illustrated, the three-bolt lock being desirable as the side locking bars may be located at the point of maximum load when the car is carrying material in bulk. Seventh, by employing a three-bolt lock and an operating lever it is possible to seal the 130

operating lever and the door can therefore not be opened without breaking the seal, nor can it be opened from the inside of the car. Eighth, the type of structure employed can be used on any style of freight or stock car, whether constructed of steel or wood. Ninth, the present structure does away with the danger of breakage by heavy trucks backing into the door opening, such breakage in the car being very marked in the style of the car being used at the present time. That is a heavy truck when backing against the car will have a tendency to break or bend the castings supporting the door rollers, causing the rollers to jam and making it necessary to slide the door along by crowbars or the like. The channel irons guiding the lower edge of the door are also liable to be bent by trucks and the like, but this is avoided in the present instance by the guide lugs employed. Tenth, sealing of the door against weather and entrance of cinders is readily accomplished in the present instance as the strap irons enclosing the door and lining the door opening overlap approximately one-quarter of an inch. These overlapping edges form guards or step-like formations which permit the insertion of a sealing medium such as burlap, tar paper or the like, and when such seal is employed leakage from rain or otherwise is entirely prevented. Eleventh, grain carried in bulk may be readily handled by a structure of this kind, but the car should be equipped with a small door above the center of the car for the purpose of loading. If special sealing is required, strips of tar paper can be placed entirely around the edge of the door and the door when closed will then be sufficiently tight to exclude moisture, retain grain, etc. When loading, the cars will have to be unloaded into a bin and the door will open sufficiently to allow the grain or other material to flow freely until such time as the door can be entirely opened and the grain handled by hand. Again, it can be readily seen that the car can be equipped with floor traps which may be opened for unloading purposes if desired.

Having thus described my invention, what I claim and desire to secure by Letters Patent is—

1. A car of the character described having a door opening therein, a track pivotally

supported above the opening, oppositely tapered studs on the car and track, reversible links provided with oppositely tapered openings to engage the studs connecting the track and car to permit inward and outward movement of the track, a door, rollers on the door engaging the track, the said door being capable of longitudinal and lateral movement to open and close the door opening. 65

2. A car of the character described having a door opening therein, a track pivotally supported above the door opening for inward and outward movement thereof, means for taking up the wear of the pivotal connections, a door, rollers carried by the door and engaging the track, the said door being capable of longitudinal and lateral movement to open and close the door opening. 70

3. A car of the class described having a door opening therein, plates secured to the car adjacent the door opening and having tapered studs thereon, a track, plates secured to the track having tapered studs thereon and a link having tapered openings 80 therein to receive the studs on the plates to provide a pivotal mounting for the track, and a door suspended from the track for longitudinal and lateral movement. 75

4. A car of the class described comprising a door opening, a track pivotally mounted above the door opening for inward and outward movement, the said track comprising a channel member having a long and a short leg connected by a web, the short leg being spaced from the pivotal supporting means for the track and forming a runway, a door, rollers on the door adapted to engage the short leg of the track and lying below the plane of the track supporting means, the said door being capable of longitudinal and lateral movement. 85 90

5. A car of the class described having a door opening therein, a track pivotally mounted above the door opening for inward and outward movement, a door, rollers on the door engaging the track and permitting longitudinal and lateral movement thereof, a lock for the door comprising sliding rods and keepers, one of the keepers forming a stop to prevent inward movement of the track and door when the same is in open position. 100 105
